UNITED STATES PATENT OFFICE.

JOSEPH C. DUNHAM, OF NORMAN, OKLAHOMA TERRITORY.

AUTOMATIC WAGON-BRAKE.

SPECIFICATION forming part of Letters Patent No. 549,563, dated November 12, 1895.

Application filed January 28, 1895. Serial No. 536,470. (No model.)

To all whom it may concern:

Be it known that I, JOSEPH C. DUNHAM, a citizen of the United States, residing at Norman, in the county of Cleveland, Oklahoma Territory, have invented certain new and useful Improvements in Automatic Wagon-Brakes; and I do hereby declare the following to be a full, clear, and exact description of the invention, such as will enable others skilled in the art to which it appertains to make and use the same.

My invention is an automatic wagon-brake; and it consists in the novel construction and arrangement of its parts.

In the accompanying drawings, Figure 1 is a top plan view of a wagon with my brake attachments applied thereto. Fig. 2 is a side elevation of a wagon, showing my means of releasing the brake-shoes from contact with the hind wheels.

The object of my invention is to produce an automatic brake that will automatically brake a wagon when going downgrade without the necessity of the team holding back and to brake as it releases its grasp from the wheels when the draft is on and a brake that can be released by the driver from the box.

My invention is described as follows:

A and B, respectively, represent the front and rear parts of the running-gear.

C represents the brake-bar, and c represents the brake-shoes.

To the rear part of the rear running-gear is secured two springs d, which may be elliptical or in any other proper shape. To these springs are secured the rear ends of rods e, the front ends of which are threaded and pass through the bar C, and on the threaded ends of these rods e, and working against the front face of the brake-bar are nuts f. These nuts are provided with perforations, and the threaded ends of said rods are also provided with perforations, so that safety-pins f' may be passed through said perforations to prevent the nuts from turning. The purpose in having the front ends of said rods e threaded and having working thereon threaded nuts f is to increase or decrease the tension of the springs d, thus lessening or increasing the friction of the brake-shoes against the periphery of the wheels, so as to accommodate

said friction to the size of the wagon or the weight of the load.

To the rear hounds are secured V-shaped rods h, their upper ends h' secured to the upper face of the hounds and passing over and in front of the brake-bar C, their lower ends h² passing under said brake-bar and secured to the lower face of the hounds. In the V-point of these bars is a perforation, to which is pivoted the outer ends of levers i, and inside of said pivotal points, about six or eight inches therefrom, are projections i', their rear ends being secured to the brake-bar and their front ends pivoted to said levers i. Thus, as will be seen, these V-shaped rods act not only as fulcrums for the levers i but guides for the brake-bar C. The inner ends of said levers are of considerable length, each passing beyond the opposite side of the coupling-tongue, and to the ends of these levers are secured the rear ends of chains j, their front ends being secured to the hook or ring j' in the rod k, the front end of said rod being hooked in a link k', which passes around the king-bolt of the wagon, and to the front end of said link are secured the rear ends of chains l, their front ends being secured to the double-tree m, and on the top of the tongue n is secured a strap o, having a longitudinal slot p, the tongue n being provided with a corresponding slot, and through this slot p, through the central perforation of the doubletree and through the corresponding slot in the tongue, runs the doubletree-pin, thus enabling the doubletree-pin to work backward and forward to the extent of the length of the slot p.

The operation of my brake is as follows: The springs d, through the rods e and the brake-bar C, keep the brake-shoes c tight up against the periphery of the rear wheels. When the horses pull on the doubletree, the long ends of the levers i are pulled forward by means of the mechanism described, which throws the brake-bar C forward and relieves the wheels from contact with the brake-shoes c. When the horses stop pulling, (when the draft is off,) the mechanism resumes its former position by means of the springs d, and the wagon is locked. Thus it will be seen that the wagon is automatically locked when going downhill or standing still.

In addition to the mechanism above described I have pivoted to the bottom and left side of the wagon-body a lever R, and to the rear edge of said lever are secured the front 5 ends of chains r, while their rear ends are secured to the front ends of the chains j, and to the right-hand end of said lever is secured a rod S, the front end of which is secured to a usual brake-rod mechanism T, and when the 10 driver wishes to unbrake the wagon to back it, or for any other purpose, he pushes the brake-lever t backward.

Having described my invention, what I claim as new, and desire to secure by Letters 15 Patent, is—

In an automatic wagon brake, consisting of the springs d, rods e, brake bar C, nuts f,

levers i, and means for operating said levers; the V-shaped rods h, their ends h', secured to the upper face of the hounds and passing 20 over and in front of the brake bar C; their lower ends h², passing under said brake bar and secured to the lower face of the hounds, acting at once as a guide for the brake bar and fulcrum for the levers i, substantially as 25 shown and described and for the purposes set forth.

In testimony whereof I have affixed my signature in presence of two witnesses.

JOSEPH C. DUNHAM.
